UNITED STATES PATENT OFFICE

WILLIAM T. GRESSET, OF RICHMOND, VIRGINIA.

DESIGN FOR A CIGAR.

SPECIFICATION forming part of Design No. 27,525, dated August 17, 1897.

Application filed March 27, 1897. Serial No. 629,618. Term of patent 14 years.

To all whom it may concern:

Be it known that I, WILLIAM T. GRESSET, a citizen of the United States, residing at Richmond, in the county of Henrico and 5 State of Virginia, have invented and produced a new and original Design for Cigars, of which the following is a specification.

Referring to the drawings which are a part hereof, Figure 1 is a perspective view of the 10 cigar; Fig. 2, a side elevation thereof; Fig. 3, a cross-section on the line 3 3 of Fig. 2, and Fig. 4 of another side of the cigar.

The leading feature of this design consists of a cigar twisted longitudinally and formed 15 substantially triangular in cross-section throughout nearly its entire length.

Referring to the drawings by letters, *a* designates the lighting end, which is flat, as usual, and is triangular in cross-section, and 20 *b* the mouth end, which is tapered and rounded, as usual.

The body of the cigar is substantially triangular in cross-section from its lighting end to near its mouth end, where it tapers into the rounded part of the mouth end. ²⁵

The letters *c*, *d*, and *e* designate the three comparatively flat sides, the corners being rounded off, as at *f*.

The cigar is twisted longitudinally, somewhat in the manner of a corkscrew, making 30 about one turn throughout its length.

I claim—

The design for a cigar substantially as herein shown and described.

In testimony whereof I affix my signature 35 in presence of two witnesses.

WM. T. GRESSET.
